UNITED STATES PATENT OFFICE.

HERBERT G. IRWIN, OF SPUR, TEXAS.

VAPORIZING ATTACHMENT FOR INTERNAL-COMBUSTION ENGINES.

1,290,208.

Specification of Letters Patent.

Patented Jan. 7, 1919.

Application filed December 3, 1917. Serial No. 205,197.

To all whom it may concern:

Be it known that I, HERBERT G. IRWIN, a citizen of the United States, residing at Spur, in the county of Dickens and State of Texas, have invented certain new and useful Improvements in Vaporizing Attachments for Internal-Combustion Engines; and I do hereby declare the following to be a full, clear, and exact description of the invention, such as will enable others skilled in the art to which it appertains to make and use the same, reference being had to the accompanying drawings, and to the letters and figures of reference marked thereon, which 10 form a part of this specification.

This invention relates to new and useful improvements in attachments to internal combustion engines, providing means for vaporizing and introducing into the cylinders a liquid fuel or decarbonizing solution while the motor is in motion, for the purpose of removing carbon deposit in the cylinders, or introducing a light highly combustible fuel to aid in the combustion of 25 heavy fuels.

The invention comprises various details of construction, combinations and arrangements of parts which will be hereinafter fully described, shown in the accompanying 30 drawings and then specially defined in the appended claim.

I illustrate my invention in the accompanying drawings which, with the letters of reference marked thereon, form a part of 35 this specification and in which:

Figure 1 is a central vertical sectional view through the device, and Fig. 2 is a front elevation.

Reference now being had to the details of 40 the drawings by letter:

N designates a casting which is flanged as at N⁷ near the rear thereof, and forming means whereby the device may be secured to the running board B' of an automobile.

45 Said casting has tapering nipples N⁶ passing through apertures in the running board. Pipes N³ and N⁴ are respectively connected by means of the couplings N⁵ to said nipples. The casting has parallel ducts N' and

50 N² leading through the nipples, the former communicating with the pipe N³ and the latter with the pipe N⁴. Said casting has formed therein a cylindrical outlined vertical opening in which a rotatable plug O

is journaled, and which plug valve has a 55 flange O' resting upon the top of the casting, and a handle O² for turning the plug. The lower end of the valve has a screw O⁵ fitted in a hole in the bottom thereof, and interposed between the screw and the bottom of the casting is a washer O⁶. The plug is provided with angular outlined ducts O³ and O⁴ formed therein and which, at their adjacent ends, open into a narrow transverse slot O⁷ formed in the valve. The 60 ducts O³ and O⁴ are designed to register when the valve is in certain positions respectively with the ducts N' and N².

The outer face of the casting is recessed 65 away, as at P, at a location about the slot O⁷ to permit air to pass freely into the ducts of the valve.

In operation, when the valve O is positioned so that the duct O³ will register with the duct N' and the duct O⁴ with the duct N², the suction from the manifold through the pipe N³, which communicates therewith, will cause fuel to be drawn from the pipe N⁴ and ducts N² and N⁴. The slot O⁷ being narrow, the suction from the manifold will 70 not only draw the oil up through the duct O⁴, but will also draw in air through the slot O⁷ and which air commingles with the oil before it enters the cylinder of the engine.

What I claim to be new is:

An attachment for engines to prevent carbonization, etc., consisting of a casting having integral nipples adapted to be passed through the wall of the running board of an automobile, with flanges at the rear of the casting for attachment to the running board, said casting provided with ducts leading transversely through the same and said nipples, pipes connected to the nipples, the forward portion of the casting having a vertical cylindrical outlined opening, a plug valve mounted therein, the plug provided with angled ducts the adjacent ends of which lead through the opposite walls of a narrow transverse slot formed in the valve and in alignment with each other, the wall of the recess adjacent to the slot being recessed.

In testimony whereof I hereunto affix my signature in presence of two witnesses.

HERBERT G. IRWIN.
